CONCRETE BLOCK MACHINE

Louis Gelbman, Yonkers, N. Y.

Application December 9, 1930, Serial No. 501,029

9 Claims. (CL. 25—41)

This invention relates to new and useful improvements in a concrete block machine, and is directed to similar subject matter as that disclosed in my prior patent application, Serial No. 5 422,984, filed on January 24th, 1930.

In a concrete block machine which has a mold resiliently suspended and means for jolting the mold vertically, and which has a feed drawer which travels transversely across the top of the mold to charge the latter element, it should be 10 recognized that such traveling of the mold tends to produce stresses and bending upon the resilient mounting of the molding which wears it out in undue time.

It is an object of this invention to provide a means to prevent such feed drawer from pushing the mold materially out of line relative to the jolting mechanism and thus relieve undue stresses and wear.

It is another object of this invention to provide rollers associated with the means for preventing undue stresses, which rollers are adapted to support the feed tray loosely so that the latter element may pivot during the jolting of the mold 25 and rock and roll for reducing caking effects of the material within the feed drawer and facilitate jolting. In practice, the feed drawer must deliver a larger charge of material than the mold can accept, and since this material is exposed to 30 jolting it tends to cake.

In concrete block machines which have a feed drawer and a shutter capable of riding beneath a hopper, it has been found that there is a tendency for the material passing through the hopper 35 and into the feed drawer to leak out from the joint between these parts. It is another object of this invention to provide an efficient seal at the sides of the hopper to prevent such leakage.

In concrete block machines, it is customary to 40 place pallets within the mold and then to enter the material to be formed into the building block into the mold on top of the pallets. This material leaks around, and gets on bottom of the pallet and soon becomes hardened at certain places 45 which would tend to hold subsequent pallets crooked and form blocks which were not true.

It is still a further object of this invention to 50 arrange support bars connecting the cores with the remaining portions of the mold so as to expose 55 knife shaped top edges upon which the pallets should rest so that during jolting any material which passes the pallet would run down along the knife edge and not deposit at the top which would cause subsequent pallets to be in crooked positions. The trade requires blocks of different sizes, and

it is proposed to so design the mold that it may be changed for producing blocks of different size. Such an alteration would necessarily mean a change in the stripping mechanism which strips the blocks from the mold.

It is another object of this invention to arrange an inclined element beneath the mold so that waste from the mold may run off, and to pass posts through this inclined element for supporting a frame carrying stripper rods so that the 10 rods may be changed to accommodate different molds, and said rods to connect with stripping mechanism below said inclined element whereby a change of the stripping rods may take place without disturbing the remaining portion of the 15 stripping mechanism.

The intention of the feed drawer is to deliver a charge of material over the mold so as just to completely fill the mold. In practice, this is not possible, and consequently the feed drawer is 20 arranged to deliver a charge slightly greater than is needed. During the jolting, this excess charge has its consistency changed so that it becomes materially hard. Upon the return of the feed drawer to receive another charge, some of this 25 material will be forced upwards and tend to prevent the complete return of the feed drawer.

It is still a further object of this invention to provide a means which would allow the full return of the feed drawer even though excess 30 material projects above the top of the feed drawer.

It is a further object of this invention to provide means to direct the filling of the feed drawer so that it has the correct amount of material 35 when it moves over the mold.

It is still a further object of this invention to provide a means for breaking down the caking of the excess material in the feed drawer. It is particularly proposed to actuate this means during the jolting of the mold so that the caked material falls quickly into the mold together with the remaining charge.

In building block machines of the type mentioned, there is the necessity of two main controls, namely a control for causing the feed drawer to move from its filling position into its discharging position, and a control for causing the stripping mechanism to move upwards to strip blocks from the mold.

It is another object of this invention to provide a means for locking the operation of the feed drawer when the stripper rods are up, and also for locking the operation of the stripper rods when the feed drawer is out to prevent possible 55

damage upon incorrect operation of the controls.

It should be noticed that the mold of the machine is a multiple one which forms a plurality of blocks at one time. Since concrete blocks are quite heavy, an efficient means is necessary to take away the blocks as quickly as they are produced or the machine could not work at full capacity.

It is another object of this invention to provide a means and a method to take away the blocks in a group from the mold so as not to interfere with efficient operation of the machine.

A further object of this invention is to provide automatic means for supporting the jolting of the mold upon the extension of the feed drawer and to time this jolting for a predetermined period.

Another object of this invention is to provide manual means to add as much time whenever necessary to the automatic jolting time of the mold. It sometimes occurs that for some reason or other, the blocks have not been sufficiently packed into the mold, and the provision of an extension of time of jolting is very requisite when this occurs.

Another object of this invention is to provide manual means for stopping the jolting at any time as a safety device in the event that an emergency arises.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 17 is a fragmentary sectional view of one of the jolt housings shown in Fig. 1.

Fig. 18 is a schematic wiring diagram of the electrical parts of the machine.

Fig. 19 is a perspective view of the apparatus used for removing the blocks when stripped from the mold, and

Fig. 20 is a perspective view of one of the trays used in conjunction with the rack shown in Fig. 19.

The concrete block machine includes a horizontal mold 10, means for jolting the mold, means for stripping blocks from said mold, a stationary hopper 11 to one end of the mold, a feed drawer 12 supported for moving from under said hopper to a position on said mold, a stationary plate 13 closing the bottom of said feed drawer when beneath the hopper, a shutter 14 connected with said feed drawer for closing the bottom of the hopper 11 when the feed drawer is over the mold, and means for moving said feed drawer.

The mold 10 is opened at the top and at the bottom and is formed with several partitions 15 to divide it into various compartments so as to form a plurality of blocks each time. Each of the compartments have cores 16 for forming the hollow openings in the blocks. These cores are supported by strips 17 connected with the sides of the mold. The tops of the strips 17 are sharpened so as to represent knife edges clearly illustrated in Fig. 5. It is customary to place pallets in the various sections of the molds and upon the strips 17 before the material is settled into the mold. Thereafter, when the material is stripped from the mold, it is stripped together with the pallets and thus placed through the various treatment operations. The knife edges act to extreme advantage in that when some of the concrete from within the mold passes the pallet and deposits upon the strips 17 through the vibration of the mold, it necessarily will slip off from the knife edges so that subsequent pallets placed within the compartments of the mold will rest true upon the strips for forming blocks having square corners. Should the pallets be at inclinations due to the building up of some of the concrete on the strips, crooked blocks will be produced.

On the longitudinal sides of the mold 12, as clearly shown in Figs. 1, 3, and 4, support strips or shims 18 are secured and support tracks 19. The tracks comprise spaced bars between which rollers 20 are rotatively supported and project above the top edges. These rollers are intended to support the feed drawer 12 when the latter element is moved over the mold. One advantage of supporting the feed drawer upon the rollers is that during the vibration of the mold, it will joggle and rock on the rollers which will aid to discharge its contents against the caking effect of the concrete left over from a previous charge. Further, the tracks and rollers serve to reduce the frictional contact of the feed drawer 12 as it passes from under the hopper onto the mold so as not to cause stresses which would place the mold out of alignment, producing undue wear.

The means for jolting the mold 10 has been explained in minute detail in my copending application, Serial No. 422,984 filed January 24th, 1930. Briefly, the means consists of a frame 21 attached upon the bottom of the mold and suitably cut out so as not to hinder the passage of stripper rods to lift the pallets from the mold, or the passage of concrete material which gets past

the pallets downwards. Several jolt housings 22 support the frame 21. Preferably these jolt housings are arranged at each of the corners of the mold. Each jolt housing comprises an upper casing section 23 slightly spaced from the lower casing section 24 resiliently supported by an expansion spring 25 within the casing sections, tending to urge them apart. A bolt 26 is extended through the jolt housing and serves to limit the amount of possible motion in one direction, while the small spaces between the casing sections limits the amount of possible motion in the other direction. Nuts 27 are fixed upon the bolt 26 so as to be adjustable to arrange for the correct amount of clearance. A transverse shaft 28 is supported across the bottom of the frame 21 by standards attached upon the frame, and offset weights 29 are fixed upon the shaft so that upon rotation of the shaft jolting occurs. The casing sections 23 or 24 are so arranged so as to limit possible motion of the sections to the vertical to cause the jolting to occur vertically. Covers 30 are placed over the weight and attached upon the frame 21 so as to guard the weights. A pulley 31 is attached upon one end of the shaft 28 and carries a belt 32 extended over a pulley 33 upon the shaft of a motor 34 supported upon I beams 35 included in the frame of the machine. The lower sections 24 of the jolt housings are attached upon a frame structure 36^a insulated with a rubber pad 36^b upon the frame structure 36 having a base portion 37 for resting upon the ground. Preferably, the frame structure should include four vertical members at the corners beneath each of the jolt housings. A compartment is enclosed by this frame, and plates 38 are arranged upon the sides of the frame to conclude the enclosing of the compartment. Within this compartment the stripping mechanism is arranged.

The means for stripping the blocks from the mold comprises slides 39 arranged to slide vertically upon guides 40. A shaft 41 is rotatively supported between the plates 38 and carries radial arms 42 pivotally connected with one of the ends of links 43 which are pivotally connected at their ends on the slide 39. Posts 44 project from the slide 39 and support a horizontal frame 45 from which a plurality of stripping rods 46 project. These stripping rods are so arranged as to be at the corners of the various compartments forming the blocks in the mold 10, as may be seen from an inspection of Fig. 3. Thus when the stripping mechanism moves upwards, the pallets which support the various molded blocks will be moved upwards and out from the mold. An inclined sheet member 47 is arranged immediately below the frame 45, and the posts 44 pass through oil packing elements 48 mounted on the inclined sheet member. The sheet member 47 serves to protect the stripping mechanism from the concrete material which falls past the pallets.

It is very desirable in a machine of this type to arrange it so that the mold may be replaced by a different mold so that blocks of different sizes may be manufactured. A change of the mold will raise the necessity of changing the positions of the stripper rods 46. The frame 45 is so constructed that such changes are readily possible. Preferably, spare threaded apertures should be provided so that the stripper rods may assume new positions. A feature of this invention is that a change in the position of the various stripper rods can be made without disturbing the stripping mechanism. Since such change occurs only above the sheet member 47, it will be recognized

that it may be readily done without disturbing the mechanism below the sheet member. Lugs 49 are attached upon the frame 36 and receive side arms 49 from a container 50 which serves to receive the material sliding down the inclined sheet member 47. The container 50 is removable by merely lifting it vertically upwards, and should be emptied every now and then when it becomes too full. This arrangement is very useful in that it eliminates a lot of labor to clean the machine after a day's work in that most of the waste concrete material can be scraped off of the inclined member 47 and into the container 50.

The means for stripping the blocks also includes a sprocket 51 fixed upon the shaft 41 and connected with a chain 52 extended over an idler 53 adjustably mounted so as to be movable to new positions to correct the tension of the chain 51. The chain 52 extends over a sprocket 54 upon a shaft 55 rotatively supported by standards 56. A gear 57 is fixed upon the shaft 55 and meshes with a driver pinion 58 upon a shaft 59 parallel with the shaft 55 and directly over it, and held rotatively supported. A driver pulley 60 is fixed upon the extended end of the shaft 59 and is intended for connection with a driver belt for providing the power for the machine. A clutch is arranged upon the shaft 55 and consists of a clutch cup 61 slidably keyed upon the shaft 55 and carrying pins 62 engageable in apertures in the side of the gear 57. A spring 63 is coaxially arranged upon the shaft 55 and normally urges the clutch cup 61 so that its pins 62 are out of engagement with the gear 57. A roller 64 is supported upon a stationary axis 65 and normally bears against the cup 61 so as to hold the cup with its pins 62 in engagement with the apertures in the gear 57. The cup 61 is formed with recesses 66 at 180° from each other and so formed that when these recesses reach the roller 64, the spring 63 may urge the cup into the position, as shown in Fig. 10, in which the pins 62 are out of engagement.

A fork 67 is pivotally supported at 68, and at 45 one end carries rollers 69 engageable against the cup 61 for urging the cup so that its pins engage in the aperture in the gear 57. A link 70 pivotally connects with the free end of the fork 67 and at its other end with a lever 71. A spring 72 is arranged between the link 70 and a plate 73 supported upon the frame of the machine. The standards 56 are also supported upon the said plate 73. The lever 71 is fixed upon the shaft 74 supported by standards 75 upon the frame of the machine. When the lever 71 is manually moved, the link 70 will move correspondingly so as to pivot the fork 67 and urge the clutch cup 61 so that its pins engage the gear 57. Upon the slightest rotation from the gear 57, the clutch cup will have turned so that the recess 66 rides out from the roller 64. Then the lever 71 should be moved back into its original position, and the roller 64 will keep the clutch cup in its engaged position until the next recess 66 is reached, when 65 the spring 63 will return the clutch cup into its disengaged position. The sprockets 54 and 51 should be of the same sizes so that for each half revolution of the clutch cup 61, the shaft 41 will rotate one half revolution also and move the 70 radial arm 42 correspondingly. The parts should be arranged so that in a lowered position of the slide 39, the radial arm 42 extends vertically downwards, as illustrated in Fig. 1. Then upon a 180° rotation, the vertical arm extends upwards 75

and thus raised the stripping mechanism into its operative position.

The hopper 11 is supported by braces 16 attached upon the frame of the machine. In Fig. 5 2 these braces can be very distinctly seen extending upwards from the frame and arranged adjacent the sides of the hopper. In Fig. 1 a panel board 17 is shown attached upon the front braces 16. At the sides and at the bottom the 10 hopper 11 is formed with inverted V-shaped grooves 18 for the reception of corresponding projections from the feed drawer 12 and from the shutter 14. In Fig. 16 these V-shaped grooves are clearly shown extending the complete length 15 of the front and rear sides of the hopper. Within the hopper and arranged on the left hand end, referring to Fig. 1, there is a flap 19 pivotally supported and extending the complete width of the hopper. The hinge point is illustrated in 20 Fig. 13 by reference numeral 80. Extensions 81 are adjustably attached upon the flap 19 so as to be extendable to any desirable position relative to the top edge of the feed drawer 12. On the right hand end of the hopper, there is a 25 guide plate 82 arranged at an angle and rigidly attached. An angular extension 83 is adjustably connected with the guide plate 82 so as to be extendable to various positions. The extension 83 and the guide plate 82 extend the 30 complete width of the hopper, as may be seen from an inspection of Fig. 16. As the concrete enters the hopper, the extension will determine the piling of the concrete into the hopper so that it will not overflow over the right hand end of 35 the feed drawer onto the shutter 14. Obviously, as the extension 83 is raised or lowered, the angle of filling of the feed drawer will be adjusted, and by trial the correct amount of filling can be obtained. As the feed drawer 12 moves 40 outward to its position over the mold, excess material will be forced upwards by the extension 81 and the flap 19 which act as a shear to cut off the excess material from the feed drawer. When the feed drawer returns from its extended position 45 over the mold back to its position to the hopper, the excess of the charge which is sheared off from the top of the mold will build up at one end of the feed drawer, and for this reason an extended lip 84 is arranged upon the feed drawer so as to prevent the overflow. This built-up charge can 50 pivot the flap 19 inwards so that the feed drawer 12 may return to its fully retracted position. Of course, if not for the flap, upon the return of the feed drawer its excess material would get in 55 between the hopper and the lip 84 and prevent proper closing of the drawer. In the event that the lip was not provided, the excess material would overflow and stop up the entire machine. The feed drawer 12 is open at its top and at its 60 bottom, as clearly shown in Figs. 13 and 15. Along the longitudinal sides, it is formed with projecting V portions 85 which ride into the V grooves 18 formed in the hopper so as to provide a seal to prevent the leakage of the material from the hopper through the joint of these parts. As 65 shown in Fig. 13, the ends of the feed drawer are hollow for the reception of means to prevent the caking of the material within the feed drawer. The opened portion of the feed drawer should be of such size that it fits directly beneath the hopper and held so that when positioned over the mold it covers the entire opened top of the mold.

A means is provided within the feed drawer to 75 prevent caking of the material, and this means

comprises a plurality of longitudinal rods 86 slidably mounted in one end of the feed drawer and through the other end so as to project to the exterior. Rollers 87 are mounted upon the extended ends of the rods 86. Brackets 88 are attached upon the end of the feed drawer and encircle the various rods 86. These brackets are formed with heads 89 receiving pins 90 extended through the rods 86 so as to prevent rotation of the rods and limit the motion of the rods to sliding only. A washer 91 is loose upon each of the rods and acts against the pins, while coaxial springs 92 are arranged upon the rods and act between the washers 91 and one of the sides of the hollow at one of the ends of the feed drawer. The action of the springs is to normally urge the rods outwards. A plurality of arms 93 are fixed upon the rods 86 and extend downwards to near the bottom of the feed drawer.

Standards 94 project from the outside of the feed drawer 12 and support a transverse shaft 95 carrying a plurality of cams 96 coactable against the rollers 87 for depressing the plungers against the actions of the springs 92. A gear 97 is fixed upon the shaft 95 and meshes with a gear 98 upon a stud shaft 99 carrying a bevel gear 100 in mesh with another bevel gear 101 upon a shaft 102 which is formed of two sections connected by a flexible coupling 103 located at the junction between the feed drawer 12 and the shutter 14. The shaft 102 connects with an electric motor 104 attached upon the outer end of the shutter 14.

The supporting of the feed drawer 12 is accomplished by overhanging portions 105 shown in Fig. 1. These overhanging portions are similar to the overhanging portions 106 of the shutter 14. These overhanging portions rest upon rollers 107 supported by spaced bars 108 attached upon strips or shims 109 fixed upon longitudinal channels 110 of the frame of the machine. These longitudinal channels 110 are supported by heavy vertical members 111 connected with a base structure 112 which is rigidly connected with the base structure 31. The rollers 107 and the rollers 20 40 45 are in line with each other so that the feed drawer 12 and the shutter 14 may be moved to their extended positions. As the feed drawer 12 moves from its position under the hopper, as illustrated, to a position on the mold 10, the shutter 14 will 50 move from the position shown on the drawings to a position beneath the hopper 11 so as to close the bottom of the hopper to prevent the material from discharging. The stationary plate 13 is supported upon the channels 110 and serves to 55 close the bottom of the feed drawer 12 when the feed drawer is beneath the hopper 11.

The shutter 14 comprises merely a flat horizontal portion 113 at an elevation corresponding with the top of the feed drawer 12 so as to close 60 the bottom of the hopper as before specified. At the sides the feed drawer is provided with V-shaped projections 114 in line with the V-shaped projections 85 and for the same purpose, that is, for riding into the V-shaped grooves 18 of the 65 hopper. Ribs 115 project from the bottom of the flat portion 113 and are formed with vertical slots 116 receiving pins 117 from lugs 118 projecting from the feed drawer 12 so as to flexibly connect these parts.

The means for moving the shutter 14 comprises links 119 having pins 120 at one of their ends engaging in apertures 121 in the ribs 115, and at their other ends pivotally connecting at 122 with radial arms 123. These radial arms 123 70 75

are fixed upon a shaft 124 rotatively mounted in standards 125 attached upon horizontal I beams 126 supported at their inner ends upon vertical I beams 127 and at their outer ends upon inclined I beams 128. These I beams constitute a portion of the frame of the machine. Counterweights 129 are fixed upon the radial arms 123 and extend to the offset side of the shaft 124 so as to counterbalance the weights of the arms 123. A brace 130 is arranged between the inclined members 128 to brace them. In addition, several vertical support members 131 are arranged beneath the I beams 126 and the braces 35 to add more rigidity to the frame.

15 A sprocket wheel 132 is fixed upon the shaft 124 and carries a chain 133 extended beneath an idler 134 adjustably mounted upon the bottom of the I beams 126 for changing the tensional tightness of the chain. The chain 133 also extends over another idler sprocket 135 adjustably mounted upon the brace members 35. The chain 133 is also extended over a sprocket 136 fixed upon the shaft 137 rotatively mounted in the standards 56.

20 A gear 138 is fixed upon the shaft 137 and meshes with the driver pinion 58. A clutch cup 139 is keyed upon the shaft 137 so as to be longitudinally slideable, and has a plurality of pins 62 engageable in corresponding openings in the 30 side of the gear 138 to couple these parts together. A spring 63 acts between the gear 138 and the clutch cup 139 to urge the parts out of engagement. A fork 67 is pivotally mounted at 68 and at its bottom end carries rollers 69 engageable 35 with the cup 139 to urge it into a position in which the pins engage. A roller 64 is rotatively mounted upon the stationary shaft and bears against the clutch cup 139 which is formed with only one recess 66 arranged so that when the 40 roller 64 engages the recess the clutch is out of engagement, and upon rotation of the clutch cup so that the roller is not engaged in the recess then the pins 62 of the clutch cup engage in the gear. The sprocket 136 is exactly one half the 45 size of the sprocket 132 so that for each complete rotation of the sprocket 136, the shaft 124 rotates one half a turn, or through an angle of 180°. A link 140 pivotally connects with the fork 67 and extends towards the side, and pivotally connects with a control lever 141 mounted 50 upon the shaft 74. This control lever extends upwards and is provided with a handle at its top end for manual manipulation. A spring 142 acts between the link 140 and the plate 73 so as to normally urge the fork 67 into a position which 55 does not cause the clutch cup to assume its engaged condition.

60 A means is also provided for locking the operation of the feed drawer 12 when the stripper rods 46 are in their up position. This means comprises an angle plate 143 attached upon the frame of the machine and formed with a slot 144 through which the control lever 141 passes. A peg 145 is slidably mounted upon the angle iron 143 and 65 is adapted in an extended position to engage in an aperture 146 formed in the lever 141 so as to lock the lever against being moved to cause operation of the feed drawer. The peg 145 pivotally connects with a bell crank 147 urged into 70 a fixed position against a stop 148 by a spring 149. A bolt 150 projects from the guide 39 and in the raised position of the guide acts against the bell crank 147 so as to pivot the latter element and move the peg 145 into its locking position.

75 A means is also provided for locking the op-

eration of the stripper mechanism when the feed drawer 12 is in its extended position. This means comprises a limit projection 151 upon the shutter 14 engageable with one end of a lever 152 pivoted at 153 and having its bottom end pivotally connected with a bell crank 154. This bell crank is pivotally mounted at 155 upon the angle iron 143, and an expansion spring 156 acts between the bell crank and the angle iron 143 to disengage the bell crank from an aperture 157 formed 10 in the lever 71. This lever 71 extends through a slot 158 formed in the angle iron 143.

15 Upon the panel board 77 there is attached a pair of grease containers 159 which connect up with hand pumps 160 for connecting with a lubrication system, not illustrated in detail on the drawings, but for the purpose of lubricating the various rollers 20 and 107 and the other moving parts of the machine, such as the stripping mechanism and the feed drawer mechanism. In Figs. 20 10 and 12 the bearings 56 have been shown in detail. It should be noticed that the bearings comprise one integral mass of material formed with several large projections 161 provided with caps 162 constituting the bearings for holding the shafts 25 55, 59, and 137 rotatively. It is intended that the projections 161 be properly machined so that when the standards 56 are attached in place in the machine, it will be necessary to only align one of the shafts 55 into its true horizontal position and automatically the other shafts 59 and 137 will assume aligned positions. This arrangement saves a lot of time in the assembling of the machine in that great accuracy and skill is not necessary.

35 Various other pieces of electrical apparatus are attached upon the panel 77 and upon the frame of the machine. Briefly, they consist of a line switch 163, a starter motor timer 164, a limit switch 165 operable by a set screw 166 carried by 40 the shutter 14. In addition, there is a push button switch 167. The electrical circuit is clearly illustrated in Fig. 18. It should be noticed that the line switch 163 is of the three pole type for accommodating wiring for the three phased 45 motors 34 and 104. A starter mechanism 168 is also provided and connects with the line switch 163 for closing the circuit to the motors 34 and 104. In all, there is a timer circuit, a starter circuit, and means for providing additional vibrations or for completely stopping the vibrations. The timer circuit may be traced from the power lead 169, through the limit switch 165, and then along lead 107 to the push button switch 167. This push button switch has two movable contacts, namely 171 and 172. From the common point of these two contacts, the timer circuit continues along lead 173 to the timer 164, and then through the coil 174 of the timer and back along lead 175 to the return power lead. Thus when 60 the limit switch is closed, the timer starts operating by having its switch 176 closed. The closing of switch 176 immediately starts the electric motors 34 and 104 in that a complete circuit will exist from the power lead 169 through the limit 65 switch 165, through the element 171 of the push button switch 167, then along through the element 176 of the timer 164, and along lead 177 through the coil 178 of the starter, which moves the three pole contacts of the starter to close the 70 circuit from the line switch 163 to the motors 34 and 104. After a predetermined time, as controlled by the timer 164, the circuit will be opened by element 176 moving out of contact. A shunt lead 179 is arranged to connect with the element 75

172 when this element is depressed manually, and to connect with the lead 177 so that the timer 164 is short-circuited and additional vibrations may be had for any length of time. In the event that 5 it is required that the vibrations be immediately ceased in any stage of the machine, it is merely necessary to break the circuit by depressing the push button switch 167 so that the element 171 is moved out from the circuit.

10 The operation of the device may be traced by assuming it in the condition as illustrated in Fig. 1. The first step would be that the operator of the machine drops a pallet into each of the sections of the mold. Then he should move the lever 141 towards himself and immediately back into original condition. This motion of the lever is transmitted to the clutch cup 139 which rotates slightly in that its pins 62 now engage the apertures in the gear 138. Power from the pulley 60 15 is transmitted by the pinion 58 to the gear 138. The shaft 137 will now rotate until the recess 66 again rides into the stationary roller 64 when the expansion spring 63 will disconnect the parts. The rotation from shaft 137 is transmitted by 20 the chain 133 to the shaft 124, which rotates one half a turn or 180° so that the radial arms 123 move around to be extended directly towards the left, as viewed in Fig. 1, and move the shutter 14 beneath the hopper 11 and the feed drawer 12 25 from beneath the hopper to over the mold. The counterweight 129 will now be at the extreme right, and serves to counteract the weight of the radial arms 123 so that the arms do not sag the moment the recess 66 reaches the roller 64. If 30 such sagging takes place, it is the equivalent as if the lever 141 were again moved and the feed drawer would go back into its original condition. For this reason, the counterweight is of great 35 importance.

40 Material from the hopper 11 which settled into the feed drawer 12 has now been moved over the mold 10. When the feed drawer is in its fully extended position, the set screw 166 acts against the limit switch 165 to close the switch and immediately starts operations of the motors 34 and 104. The motor 34 will operate the jolter of the mold 10 so as to completely pack the mold, while the operation of motor 104 will cause the rods 86 45 to reciprocate back and forth and break up possible caking of the material in the feed drawer so that it will quickly settle into the mold without necessitating additional jolting within that to which the machine is timed. The jolting will automatically cease under the influence of the timer 164, and then the operator must again move the lever 141 towards him and then release it to cause the feed drawer 12 to move back into its 50 original position.

It should be noticed that when the feed drawer 60 is in the extended position, the operator cannot, by error, move the lever 71 and cause the stripping mechanism to operate, since it is locked as before described.

65 After the feed drawer has assumed its original position, the operator next moves the lever 71 towards him and then releases it so as to momentarily depress the clutch cup 61 and cause it to rotate and ride out from the recess 66. The shaft 55 will now rotate one half a turn, and this rotation 70 will be transmitted by the chain 52 so as to cause the radial arm 42 to rotate from its downward position to its vertical position and move the stripper bars 45 upwards. These stripper rods act against the bottom of the pallets and strip the blocks from the mold. In this condition

tion of the machine, it is impossible to move the lever 141, since it is locked against such motion, which would be injurious in that the feed drawer 12 would be projected against the stripper rods.

The operator of the machine must next move 5 the lever 71 towards him and then release it so as to cause the clutch cup 61 to again engage and have power transmitted from the driver shaft 59 to the radial arm 42 for lowering the stripper rods. The cycle is then repeated.

10 It has been found that in order for the machine to operate efficiently, apparatus and a method must be provided for unloading the blocks which are stripped from the mold. This is accomplished by the provision of an overhead 15 track 180. A power hoist 181 is slidably mounted upon track 180, and is provided with a cable 182 which supports a fork 183 to accomplish the unloading. This fork is formed by spaced U shaped arms 184 turned upon their sides so as to have 20 bottom arms and top arms. The bottom arms are pointed at the fronts, indicated by reference numeral 185, so as to direct its slipping in beneath the pallets and over the top of the mold. 25 Stops 186 are formed upon the U shaped members of the fork so as to direct the correct insertion of the fork into place for lifting the block. The arms of the fork are of sufficient width so as to be capable of balancing the blocks. A 30 switch 187 is arranged upon the fork 183 so that the operator while moving the fork into proper 35 position may operate the switch which operates the hoist 181 to raise or lower the fork. The cable 182 from the hoist is connected to the center of gravity of the fork 183 so that the fork is 40 perfectly balanced. This point is also so arranged that it is the center of gravity of the fork and the load when the concrete blocks are in place. This is possible by the provision of balance material 188 arranged between the U shaped 45 members 184. It is intended that the fork 183 have as many arms or U shaped members as there are lines of blocks in the mold so that all 50 of the blocks may be lifted at one time.

55 After the operator has the blocks slightly lifted 45 off the mold and upon the fork, he next moves the fork along so that the hoist 184 travels along the track 180 to a rack 189. This rack is formed from several vertical members 190 held together by transverse tie members 191. A plurality of 50 horizontal angle irons 192 are arranged along sides of the rack so as to form shelves for the reception of trays. In Fig. 20 a tray 193 is illustrated for use with the rack. This tray comprises transverse members 194 supporting a plurality of 55 longitudinal members 195. It is proposed to have for each line of blocks a pair of transverse members 195 properly spaced so that the fork arms may engage between, and the block be properly 60 rested upon the tray.

65 The operator must first take one of the trays and place it in the lower shelf upon the rack. Then with the hoist, a group of the blocks which are stripped from the machine are deposited upon this tray. Next another tray is placed upon the 70 rack immediately above the aforementioned tray and another group of blocks are placed in the second tray. In this fashion the operation is continued until the rack is completely loaded, and then it is pushed out of place and a new 75 rack brought into line for the operations to continue.

75 While I have illustrated and described my invention with some degree of particularity, I realize that in practice various alterations therein

may be made. I therefore reserve the right and privilege of changing the form of the details of construction or otherwise altering the arrangement of the correlated parts without departing 5 from the spirit or the scope of the appended claims.

Having thus described my invention, what I claim as new, and desire to secure by United States Letters Patent is:—

10. 1. A mold for a concrete block machine, comprising members for forming the outsides of the blocks, cores for forming the inner sides of the blocks, and elements connecting said members and cores and having knife shaped upper edges 15 so that material to be molded will not remain thereon and cause pallets placed in the mold to assume untrue positions.

2. In a concrete block machine, a mold supported for vertical jolting, an inclined roof structure beneath said mold to guide off seepage from said mold, stripper mechanism beneath said roof, vertical rods for said stripper mechanism passing through said roof, a frame on said rods, and vertical stripper rods on said frame.

25. 3. In a concrete block machine, a mold supported for vertical jolting, an inclined roof structure beneath said mold to guide off seepage from said mold, stripper mechanism beneath said roof, vertical rods for said stripper mechanism passing 30 through said roof, and vertical stripper rods supported on said vertical rods.

4. In a concrete block machine, a mold supported for vertical jolting, an inclined roof structure beneath said mold to guide off seepage from 35 said mold, stripper mechanism beneath said roof, vertical rods for said stripper mechanism passing through said roof, a frame on said rods, packing elements mounted on said inclined roof and slidably supporting said vertical rods, and vertical 40 stripper rods on said frame.

5. In a concrete molding machine, a horizontal mold resiliently supported for vertical jolting, a stationary hopper on one side of said mold, a feed drawer beneath said hopper and movably supported 45 for moving onto said mold, a shutter connected with said feed drawer for closing said hopper as the feed drawer moves out, longitudinal rods slidably mounted through said feed drawer and having their ends projecting to the exterior, resilient means urging said longitudinal rods outwards, fingers mounted on said longitudinal rods, and means for periodically moving said longitudinal rods inwards including cams acting against the extended ends of said rods.

55. 6. In a concrete molding machine, a horizontal mold resiliently supported for vertical jolting, a stationary hopper on one side of said mold, a feed drawer beneath said hopper and movably sup-

ported for moving onto said mold, a shutter connected with said feed drawer for closing said hopper as the feed drawer moves out, longitudinal rods slidably mounted through said feed drawer and having their ends projecting to the exterior, 5 resilient means urging said longitudinal rods outwards, fingers mounted on said longitudinal rods, and means for periodically moving said longitudinal rods inwards including cams acting against the extended ends of said rods, means for preventing rotation of said longitudinal rods, and rollers upon the extended ends of the rods acting against the cams.

7. In a concrete molding machine, a horizontal mold resiliently supported for vertical jolting, a stationary hopper on one side of said mold, a feed drawer beneath said hopper and movably supported for moving onto said mold, a shutter connected with said feed drawer for closing said hopper as the feed drawer moves out, longitudinal 15 rods slidably mounted through said feed drawer and having their ends projecting to the exterior, resilient means urging said longitudinal rods outwards, fingers mounted on said longitudinal rods, and means for periodically moving said longitudinal rods inwards including cams acting against the extended ends of said rods, 20 means being also provided for limiting longitudinal motion of said rods.

8. In a machine of the class described, a mold, 30 means for jolting said mold, a stationary hopper on one side of said mold, a feed drawer beneath said hopper and movably supported for moving on to said mold, a shutter flexibly connected with said feed drawer for closing said hopper as the 35 feed drawer moves on said mold, and limiting vibrations from the mold from reaching the hopper, a prime mover mounted upon said shutter and means for continuously agitating material in the feed drawer operated with said prime mover, 40 a shaft connecting said prime mover and agitating means, and said shaft including a flexible coupling to prevent vibrations from the mold reaching the prime mover.

9. In a machine of the class described, a shutter for closing the bottom of a hopper and flexibly connected with a feed drawer for receiving materials from said hopper and delivering them on a mold, means on said feed drawer for continuously agitating material in said feed drawer, and 50 an electric motor on said shutter and connected for operating said means, the connection between the electric motor and said means comprising a shaft with a flexible coupling for limiting vibrations from the feed drawer reaching the electric 55 motor.

LOUIS GELBMAN.
